MEANS FOR MAKING ARTICLES HAVING A POLYGONAL CROSS SECTION OR THE LIKE

Richard Lester Wilcox, Waterbury, Conn., assignor to The Waterbury Farrel Foundry and Machine Company, Waterbury, Conn., a corporation of Connecticut

Application November 10, 1941, Serial No. 418,600

25 Claims. (Cl. 10—85)

This invention relates to means and method of making articles having a polygonal cross section or the like, particularly nut blanks.

A principal object of the invention is to improve the conventional means and method of fabricating such articles, whereby a better product will result, and the possibility of injury to the incomplete article during any of the several stages through which it passes during its fabrication, as well as the tools, is reduced to the minimum. Another object is to provide for means that will shape the exterior of the article and will also permit the ejection of the shaped article therefrom in a relatively central position and with the minimum pressure against the perimeter thereof. A further object is to provide for a free movement of the article from its confining walls, as it is being withdrawn with a tool after being subjected to an operation thereby. A further object is to insure the correct action on the slug immediately after being cut from the article. A further object is to produce nut blanks having a hole, to be later threaded, extending only part way through the blank, rather than entirely through the blank, as is commonly done. A still further object being to produce nut blanks wherein the cross sectional shape of the blank differs at different places and the outside walls also differ in shape from top to bottom of the blank. Other and further objects will be apparent from the following description of a preferred embodiment of the invention and the accompanying drawings.

As illustrated and described herein the invention is applied in the manufacture of an article, such as a nut blank, having a hexagonal cross section, but not limited thereto, or to other shape. This new and novel means and method is shown and described as associated with a header, upsetting machine or the like, but it is equally adapted for use with a power press or like apparatus.

In the accompanying drawings, wherein like numerals of reference indicate like parts in the several figures;

Figure 1 is a sectional view of the applicable portion of a header, upsetting machine or the like, particularly associated with this invention, the parts in section at station 3 being taken generally upon line 1—1 of Figure 2;

Figure 2 is an enlarged sectional plan view of the forming mechanism at station 3;

Figure 2a is a perspective view of a portion of a forming member and one of the forming dies.

Figure 3 is an enlarged sectional plan view of the cluster die and associated mechanism at station 5, the parts in section at station 5 being taken generally upon line 1A—1A of Figure 3;

Figure 3a is a perspective view of a portion of the cluster die mechanism and one of its dies;

Figure 4 is a sectional view of a portion of the

cluster die mechanism, the parts in section being taken upon a plane coincident with the axis of the punch pin.

Figure 5 is a view of a blank as cut from a rod at station 1 or otherwise produced;

Figure 6 is a fragmentary sectional view of the blank as shaped at station 2;

Figure 7 is a sectional view of the blank as produced at station 3;

Figures 8 and 9 are similar views of the blank as produced at stations 4 and 5;

Figures 10, 11 and 12 are views of other forms of nut blanks that may be produced by the means and method herein disclosed;

Figure 13 is a fragmentary sectional view of the tools for producing a nut blank, generally described as an acorn nut, such as illustrated in Figure 11;

Figure 14 is a similar view of the tools for producing a nut blank, generally described as a special high nut, such as illustrated in Figure 12;

Figures 15 to 18, inclusive, illustrate the several shapes of a blank, after successive operations thereon, in the fabrication of the so-called acorn nut, as shown in Figure 11; and

Figures 19, 20 and 21 are similar views of the fabrication of the so-called special high nut.

In the drawings, the numeral 10 designates the frame or body of a header, upsetting machine or similar apparatus; 11 a die block; and 12 a backing plate. A gate 29, carrying a plurality of tools, which cooperate with those in the die block 11, has a reciprocating movement toward and away from the die block in a well known manner.

Within the die block 11 are a plurality of tools spaced apart at stations severally designated 1 to 5, inclusive. At station 1 is a cut-off die 13, guide quill 17 and collar 15, through which is intermittently fed a wire rod 14. A cut-off knife 16, actuated by mechanism (not shown) of conventional construction and operation, moves across the face of the die 13, and severs the projecting end of the rod 14 to form a blank 18.

The rod 14 is intermittently moved in the direction of its length beyond the face of the die 13 by feed mechanism (not shown) of well known construction and operation. The blank 18 so severed is carried by the knife 16, or other means, to the tools at station 2.

Fixed in the die block 11 at station 2 is a heading die 19, having a recess or cavity 25 in the face thereof. Movable in the die 19 is a pin 21, the outer end of which forms a bottom for the recess 25 when the head 22 thereon is in engagement with the backing plug 20, and is moved in one direction by a spring 23. After the blank has been subjected to pressure at this station, within the recess 25 or the like, it is ejected therefrom by a knockout pin 27 into the path of the transfer mechanism (not shown) but

which may be any one of many such mechanisms, and carried to station 3.

Fixed on the gate 29 is a punch block 30, within which is secured a plurality of punch holders 31, 32, 33 and 34, spaced so that the centers thereof are substantially coincident with the centers of the tools at stations 2 to 5, inclusive. Each punch holder at its rear end is in engagement with a backing plate 35.

Movable in punch 36 in the punch holder 31 is 10 a pin 37, having a head 38 at its rear end, which determines its forward position and also engages a stop pin 39 within a recess in the punch. Between a backing plug 40 and the head of pin 39 is a spring 41 which exerts its tension so as to move 15 the pin 37 to its forward position.

Rearward movement of pin 37 is limited by the engagement of pin 39 with the backing plug 40. In operation the pin 37 pushes the blank 18 out of the cut-off knife 16 and into the recess 25 in 20 the face of the forming die 19. The knife 16 returns to its initial position preparatory to cutting off another blank and transferring it to station 2, as before.

The blank 24 as shaped at this station is shown 25 in Figure 6, its exterior conforming with the shape of the recess 25, and a depression is formed in each end by the tips of the pins 37 and 21. As so shaped the blank has an enlarged band portion 118, a chamfered portion 119 upon one side thereof, and an annular portion that is substantially the same diameter as the blank 18 upon the opposite side, with a rounded edge.

The face of the punch 36 is recessed at 116 around the opening therethrough and whereby 35 the chamfer 119 is formed on the blank.

The annular or lower portion of the blank forms the collar of the finished nut, and the cylindrical band portion is reshaped into an hexagonal exterior.

At station 3 the die unit consists of a body member 42, which is threaded into the die block 11 with its rear end in engagement with the backing plate 12 and having an opening 43 therethrough. In the wall of this opening, at its outer 40 end, are a plurality of radial slots 44, the bottom of each of which is at an angle to the axis of the body member.

Within the opening 43 is a movably mounted die member 45, having a head portion 46 that is substantially the same diameter as the opening and provided with a plurality of radial slots 26, the bottom of each of which is at an angle to the axis of the die member 45. In the embodiment herein the slots 44 and 26 are six in number, which are equally spaced about the center and register with each other. The side walls of the slots 26 are provided with die grooves 28.

Securely held within the head portion 46 of the member 45, concentric with the axis thereof, is a die 55, having a recess or cavity in its outer face that is substantially the same size and shape as the annular portion of the blank 24.

Included in the unit at this station are a plurality of pressure dies 49, one for each of the polygonal faces on the perimeter of the nut. Each die has a flat pressure face 50 with a flaring throat face 107 at its upper end, a rearwardly flaring cheek 51 upon each side thereof, and a cam portion 48 with a cam face at each end that is at an angle to each other and to the pressure face 50. The angle of these cam faces corresponds with the angle of the bottom of the slots 26 and 44, against which they ride. A lip 106 projects laterally from each side of the pressure

die 49 and a groove 52 is in the outer wall of an upwardly projecting portion upon the top of the die. One pressure die 49 is movably mounted in each of the radial slots 26 and 44 when in register with each other, with the lips 106 within the grooves 28 in the walls of the slots 26. Thus, the pressure dies may move both perpendicularly to the axis of the die member and parallel therewith. The pressure dies 49 are moved toward their common center until the cheeks 51 of each die are in engagement with similar cheeks upon the adjacent dies by engagement of the outer angular walls of the depending portions 48 with the angular walls of the slots 44 in the body member 42. When in this position the open space or cavity between the faces 50 of the pressure dies is polygonal and substantially the same shape in cross section as that of the polygonal portion of the finished nut, being closed upon all sides with the opening at the top bellmouthed and flaring outwardly and in register with the recess in the die 55.

A garter spring 53 encircling all of the pressure dies 49, resting in the grooves 52, exerts a uniform, constant, limited pressure upon each die 49 to move it toward their common center.

A ring 54 fixed on the body member 42 prevents movement of the pressure dies in one direction when a face thereon engages said ring (Fig. 1).

Within the punch 56, fixed in the punch holder 32 is a pressure pin 57, the head 58 of which determines its forward position and also engages a backing pin 59. Between the backing plug 60 and pin 57 is a spring 61, which exerts its tension to move the pin 57 forwardly.

The blank 24, after transfer from station 2 to station 3, is projected into the cavity between the pressure faces 50 of the dies 49 by the pin 57. When so presented, the several members of the forming tools at this station are in the relative positions, substantially as shown in Figure 1. Neither of the cam faces upon the cam portion 48 of the pressure dies 49 is in contact with the adjacent angular walls of the slots 26 and 44, there being a slight open space therebetween. The pressure dies are held in their innermost position under tension of the garter spring 53, at which time a flaring throat at the open end of the hexagonal space between the inner faces thereof is formed by the angular faces 107. At this station the blank first engages the angular walls 107 of the dies, moving the dies radially outwardly against the pressure of the garter spring 53 until the blank drops into the hexagonal space between the dies and comes to rest with the annular portion on the underside thereof within the recess or cavity. The punch 56 now engages the outer faces of the pressure dies 49, which moves the same and the member 45 rearwardly against the pressure of the spring 47. The pressure dies 49 move inwardly toward their common center by reason of the engagement of a cam face on the cam portion 48 with the angular wall of the slots 44 and thereby squeezing the cylindrical band portion 118 of the blank (Fig. 6) into a hexagonal form, as shown in Figure 7, when the punch 56 has reached its forward position. This punch now recedes and the hexagonally shaped nut remains in the cavity between the pressure dies 49. The garter spring 53 by a limited pressure holds the pressure dies 49 in their innermost position, with the faces 50 thereof in engagement with the hexagonal perimeter of the blank.

The blank (Fig. 7) is projected outwardly from between the dies 49 into the fingers of the transfer mechanism, now in alignment therewith, by a knockout pin 62, having a bushing 63 at its rear end, and between which and the member 45 is a spring 64, which exerts its tension to hold the knockout pin in its retracted position. An ejecting movement is given the knockout pin 62 by a knockout rod 65, which during its forward movement engages the bushing 63. The blank (Fig. 7) is now transferred to station 4, where it is pushed out of the transfer means into an hexagonal recess 68 in the forming die 69 by a punch 66 that is in engagement with a backing plug 70, and mounted in the punch holder 67.

The cross sectional shape of the tip of the punch 66 and the outer end of the recess 68 is the same as that of the polygonal portion of the finished blank, as illustrated, hexagonal, and whereby the blank and the lower portion of the recess or cavity is substantially the same size and shape as the annular portion of the blank 24. Thus the blank is molded into its finished exterior shape with enlarged depressions in each end thereof, formed by the tip 117 of the punch 66, and a similar tip upon the end of the pin 73. The blank as shaped at station 3 has a chamfered top face and a V-shaped depression in each end (Fig. 7). With relatively hard metal the corners of the cavity of the squeeze dies are not always filled out sharply, but are left slightly rounded. At station 4 the irregularities in the blank, if any, are eliminated, the pressure upon the blank being sufficient to cause the metal to flow outwardly completely filling the cavity and producing sharp corners at the junction of the faces of the polygonal cross section. The top of the blank is flattened with a sufficient chamfer around its edge. After withdrawal of the punch 66 the blank (Fig. 8) is ejected from the recess 68 by knockout mechanism, comprising a rod 72, pin 73, between which and the rod 72 is an intermediate pin 74. A compression spring 75 surrounds the knockout pin 73 and exerts its tension so as to move the knockout pin rearwardly after the pressure of the knockout rod 72 has been withdrawn. On the intermediate pin 74 is a bushing 76, which forms a guide therefor, and an enlarged head for engagement with the knockout rod 72. The forming die 69 is mounted in sleeve 77, within which is a cylindrical backing block 78. After being ejected from the tools at station 4, the blank is transferred to station 5, where a hole is punched therethrough and the blank (Fig. 9) completed. At this station is a cluster holding die, which comprises in part a body member 80, with an enlarged head, held in the die block 11 by any preferred means, to which is secured a segmental plate 81 by the screws 82. Within the member 80 is a movable die holder 83, in the outer end of which a die 84 is fixed, and adjacent thereto an annular groove 85.

The outer end of the bore of the member 80 is provided with angular T-slots 86. Slidable within each of these slots is a T-headed die 87 having a flat inner face 88. As illustrated there are six of these dies, corresponding with the number of polygonal faces on the finished nut. Each die is formed with a lip 112 that projects into the groove 85, and thus provides an operative connection between the dies and die holder 83. When in their inner position, the face 88 of each die is in contact with the hexagonal face

of the blank and function merely to hold the blank in position. Therefore, there is an open space between each die and those adjacent thereto, illustrated in Figure 3, rather than in contact with each other, as with the pressure dies 49, as shown in Figure 2. While this open space is desirable, it is not essential. It may be reduced by substituting a thinner backing plug 90, or eliminated entirely by not using a backing plug. In this latter case the innermost position of the dies is determined by their contact with each other.

Threaded into a die holder 83 is a hollow sleeve 89, and between the head thereof and the backing plug 90 is a spring 91 which holds the die holder 83 in its retracted or withdrawn position, with the dies 87 in their closed position, substantially as shown in Figure 3.

A piercing punch 92, the operative end of which is substantially the same diameter as that of the hole in the finished nut, is held in a sleeve 94 in the punch holder 93 and backed by plugs 95 and 96. This piercing punch in rear of its operative or piercing end is slightly smaller in diameter to facilitate piercing the hole in the blank and withdrawing the punch therefrom. Under the pressure of the piercing punch the metal of the blank has a tendency to flow outwardly. This is resisted by the dies 87, the angular walls of which are in engagement with the angular walls of the T-slot 86. Thus the exterior form of the blank is preserved and held against distortion.

Through the piercing die 84, and at a right angle to the axis thereof, is a pinch pin 97, preferably, but not necessarily, having a pointed inner end and a head 98 at its outer end that limits the extent of movement thereof in one direction.

Through one wall of the member 80, and bearing against the head of the pin 97, is a pressure pin 99, which is moved inwardly by any convenient means. As shown, this mechanism comprises a rock arm 100, actuated by a reciprocating rod 101, and having an adjustable screw 102, which engages a plunger 103, surrounded in part by a spring 108 in contact with the pressure pin 99.

As the slug 110 (Fig. 1), cut from the blank by the piercing punch, leaves the blank, the pressure pin 99 is moved forward under the action of the mechanism described and its inner end is pressed against the slug, holding it against movement. When so held, the slug cannot be drawn back into the hole in the nut with the return of the piercing punch and the finished blank thereon.

After the piercing punch 92 is withdrawn, pressure upon the pin 99 is released and the slug is free to travel through the hole 103 in the die holder 83 and the opening 111, through which it drops by gravity into a receptacle arranged to receive it. The slugs are pushed through the hole 103 by succeeding slugs as they are cut from succeeding blanks.

If the dies 87 maintain the same relative position as above described during the withdrawal of the blank, the tendency would be to break off the piercing punch 92. If this occurs the blank will be left in the dies with no means of withdrawing it. The same situation would result if the punch instead of breaking off pulled out of the blank, as it would be quite apt to do, as the area of friction on the blank against the dies 87 is greater than against the punch. These and

other difficulties are overcome in this invention through movement of the dies away from the blank, sufficient to relieve the friction thereon, permitting the blank to be withdrawn without friction upon any part thereof. This limited outward travel of the dies is accomplished by movement of the die holder 83 under the withdrawal pressure or pull of the piercing punch 92, which, as soon as it is applied moves the die holder 83 outwardly against the tension of the spring 91. During this action the dies 87 ride against the angular walls 86 and travel away from their common center until stopped by engagement of a shoulder on one or more of the dies with a segment stop plate 81. All pressure upon the outside walls of the blank now being relieved, it is withdrawn with and on the punch. This radial outward movement of the dies is merely sufficient to remove the friction thereof against the walls of the blank. As soon as the blank is withdrawn from the dies the spring 91 returns the die holder 83 and the dies 87 to their former innermost positions.

The blank after being pierced is carried rearwardly on the piercing punch and stripped therefrom by its engagement with a stripper bushing 104 within a bracket 105 adjustably secured on the frame 10.

When the piercing punch 92 is withdrawn the dies 87 move slightly outwardly, that is, just enough to free the blank and allow the same to be withdrawn from the cavity between the dies and to remain on the piercing punch until stripped therefrom.

Figures 10, 11 and 12 illustrate some of the other many forms of nut blanks that may be produced by the within method and means, the dies being specially shaped therefor.

The blank 113 is formed with a collar at one end, the blank 114 being dome or acorn shaped, and the special high blank 115 cylindrical in form. These illustrative forms of blanks (113 and 114) are produced by the method and means particularly illustrated in part in Figures 13 and 14. In Figure 13 the tools are designed to produce the acorn shape blank 114, shown in Figure 11. The heading die 19 at station 2 receives the cut-off blank and is provided with a cavity, into which the blank is projected by the pin 37. This cavity is shaped so that the blank is formed with a band portion 118 that is substantially the same diameter as the cut-off blank 18. Upon the top side of the band portion is a chamfered or conical section 119 formed by the recess 116 in the punch 36, an annular portion 120 and a lower conical portion 121. The blank as so formed and shaped, illustrated in Figure 15, is then presented to the tools at station 3. At this station the conical portion 121 and the annular portion 120 are in the cavity of the die 55. The squeeze or pressure dies 49 then function as before described, giving the exterior of the band portion 118 a polygonal form, hexagonal in the illustrations, without disturbing the shape of the portions of the blank within the cavity of the die 55. This blank, so shaped, and illustrated in Figure 16, is then presented to the tools at station 4. The upper portion of the cavity in the forming die 69 is polygonal in cross section and the lower portion cylindrical in cross section, with a rounded bottom. The blank (Fig. 16) is projected into the cavity in the die 69 by a punch 122 fixed in the punch holder 67 that has a tip 123 thereon with a rounded outer end. When in the forming die 69, the metal of the blank in the

annular portion 120 and conical portion 121 flows under the pressure of the punch 122, filling the rounded cylindrical bottom of the cavity and giving that portion of the blank a domed shape at the same time the tip 123 forms a recess 130 in the blank, and the metal in the band portion 118 flows upwardly but still confined within the cavity in the die 69. The blank as so formed and illustrated in Figure 17 is then presented to the tools at station 5, where it is projected into the cavity in a die 131 held in a sleeve 132. The tip 124 on the punch 125 in the sleeve 94 has a flat end face that gives the hole 130, formed by the punch 122 its finished shape and size. In this operation the metal displaced by the punch flows upwardly, forming a longer face on the polygonal portion and reducing in height the chamfered portion 119. The blank as thus shaped is ejected from the die 131 by the knockout pin 133, and is illustrated in Figures 11 and 18.

In Figure 14 there are illustrated the tools utilized to form a blank, shaped substantially as shown in Figure 12. Station 1, where the blank is cut from the rod, is omitted. In the fabrication of the blank 18 to produce such a completed blank (Fig. 12), the first operation is by the tools at station 2. The blank 18 is projected into the cavity in the heading die 19 and the band portion 126 with an adjacent chamfered portion 127 formed upon one end thereof under pressure of the punch 36. Preferably, but not necessarily, the body 128 of this blank is substantially the same diameter as the blank 18. The blank so shaped, illustrated in Figure 19, is presented to the tools at station 3, with the body portion 128 in the cavity in the die 55. The squeeze dies 49 at this station shape the collar portion 126, as heretofore described for other blanks at station 3. The flow of metal by this die pressure does not change or distort the shape of the body portion 128, which is confined within the cavity in the die 55. The blank so shaped, illustrated in Figure 20, is presented to the tools at station 4. The metal displaced by the punch 129 flows upwardly, extending the height of the polygonal band portion and reducing the height of the chamfered portion 127, producing the finished blank, substantially as illustrated in Figure 21.

A hole may be formed in the blank in the manner set forth in relation to the blanks shown in Figures 17 and 18, or they may be made solid (Fig. 21) and the hole drilled therein, which ever may be the most convenient or desirable. If the hole is to be drilled a depression 134 is preferably formed in either one or both ends, as may be desirable, by the pressure and knockout punches, as shown at stations 2, 3 and 4, of Figure 14.

By the method and tools shown herein a nut or similar blank is produced, part hexagonal and part cylindrical, the cylindrical portion being held against distortion or metal flow, while another cylindrical portion, by means of pressure against the walls thereof, is reshaped into a polygonal cross section.

The disclosure herein is given merely as one embodiment of the present invention, which is not to be considered as limiting the invention, the scope thereof being determined by an understanding of the present disclosure as one embodiment thereof and as particularly pointed out in the appended claims.

What is claimed is:

1. In mechanism of the character described; a die unit having a plurality of pressure dies ar-

ranged about a common center; positive means for moving the dies toward said common center; and independent means applying pressure to said dies to move the same toward said common center.

2. In mechanism of the character described; a die unit having a plurality of pressure dies arranged about a common center; means for moving the dies toward said common center; and encircling resilient means applying pressure to said dies to move the same toward said common center.

3. In mechanism of the character described; a die unit having a plurality of pressure dies arranged about a common center; means for moving the dies toward said common center; and a garter spring engaging all of said dies and applying pressure thereto to move the same toward said common center.

4. In mechanism of the character described; a die unit having a plurality of dies arranged about a common center; means, as a transient member for moving said dies away from said common center; positive means for thereafter moving said dies toward said common center and shaping the exterior of the transient member between the inner faces thereof; means for ejecting the transient member from between said dies; and resilient means for holding said dies against said transient member while being ejected.

5. In mechanism of the character described; a die unit having a plurality of dies arranged about a common center and when adjacent thereto the inner faces thereof surround a chamber formed thereby, each die having a flaring wall at one end of the inner face thereof, which flaring walls form a throat for said chamber; a transient member for moving said dies away from said common center by engagement with said flaring throat; means for thereafter positively moving the dies toward said common center and applying pressure to the walls of the transient member and thereby shaping the exterior thereof; ejecting means for moving the transient member out of said chamber; and independent means applying pressure to each die toward said common center.

6. In mechanism of the character described; a die unit having a plurality of pressure dies arranged about a common center; positive means for moving said dies away from said common center, said dies having an intermeshing engagement with one of said positive moving means; and independent means that exerts a pressure upon said dies to move the same toward said common center.

7. In mechanism of the character described; a die unit having a body member with an opening therethrough and a plurality of radial slots therein; a plurality of dies, one in each of said slots; a second member movable within the opening in the body member and having a plurality of radial slots corresponding in number and position with the slots in the body member, all of said slots having inclined bottom walls; a plurality of dies, each having a portion thereon with oppositely disposed cam faces, one die being movable within each of the registering slots in the body and second member; a punch movable into and out of engagement with the dies, and when in engagement therewith moving the dies axially in the body member and causing them to travel toward their common center by the engagement of the cam faces thereon with the angular walls in the body member; and independent means en-

gaging each die and exerting a pressure thereon that tends to move the dies toward their common center.

8. In mechanism of the character described; a die unit having a body member with an opening therethrough and a plurality of radial slots therein; a plurality of dies, one in each of said slots; a second member movable within the opening in the body member and having a plurality of radial slots corresponding in number and position with the slots in the body member, all of said slots having inclined bottom walls; a plurality of dies, each having a portion thereon with oppositely disposed cam faces, one die being movable within each of the registering slots in the body and second member; a punch movable into and out of engagement with the dies, and when in engagement therewith moving the dies axially in the body member and causing them to travel toward their common center by the engagement of the cam faces thereon with the angular walls in the body member; and independent means engaging each die and exerting a pressure thereon that tends to move the dies toward their common center, said dies being positively moved away from their common center by the second member by engagement of the cam faces thereon with those on the second member.

9. In mechanism of the character described; a die unit having an opening therethrough and a plurality of radial slots therein; a plurality of dies, one in each of said slots; a second member movable within the opening in the body member and having a plurality of radial slots corresponding in number and position with the slots in the body member, all of said slots having inclined bottom walls; a plurality of dies, each having a portion thereon with oppositely disposed cam faces, one die being movable within each of the registering slots in the body and second member, said cam faces upon the dies projecting into said slots and in one of the relative positions of the body and second member having radial movement therebetween.

10. In mechanism of the character described; a die unit having an opening therethrough and a plurality of radial slots therein; a plurality of dies, one in each of said slots; a second member movable within the opening in the body member and having a plurality of radial slots corresponding in number and position with the slots in the body member, all of said slots having inclined bottom walls; a plurality of dies, each having a portion thereon with oppositely disposed cam faces, one die being movable within each of the registering slots in the body and second member; and stop means for limiting the movement of the second member relatively to the body member, said dies being movable radially independently of said member at said limit of movement of the second member.

11. In mechanism of the character described; a die unit having a body member with an opening therein, in the walls of which are a plurality of radial slots with angular bottom walls; a second member having a plurality of slots which register with those in the body member, these slots having guide grooves in the side walls thereof; a plurality of dies mounted in said radial slots and movable toward and away from the center of said members, having intermeshing engagement with the grooves in the second member; and means for actuating the second member axially in one direction, thereby imparting movement to the dies.

12. In mechanism of the character described; a die unit having radially movable dies therein; a piercing punch; means for actuating the punch, whereby it will pierce the blank held in the cavity between said dies; a contact member mounted in said unit; and positively actuated means for actuating said contact member, whereby it will engage and hold the slug cut from the blank, said means being timed so as to engage the slug as it is cut from the blank and released after the punch has been withdrawn.

13. Mechanism for producing a nut or similar blank having a portion thereof substantially cylindrical in cross section and another portion substantially polygonal in cross section comprising in part a die to receive one end of a cylindrical portion of a workpiece, in which the workpiece is held rigid during the upsetting thereof, and a squeeze die that applies pressure to the workpiece outside of the die and without disturbing the metal of the cylindrical portion.

14. Mechanism for forming a nut or similar blank, comprising in part, a cavity die that receives a portion of the blank, and squeeze dies that apply radial pressure to the outer wall of that portion of the blank not within the cavity, reshaping the same, and without disturbing the shape of that portion of the blank within the cavity.

15. The combination with a squeeze die having a plurality of pressure dies that move toward and away from a common center, of a cavity die adjacent thereto, the cavity therein being substantially an extension of the open space between the inner faces of the pressure dies.

16. The combination with a squeeze die having a plurality of pressure dies that move toward and away from a common center, of a cavity die adjacent thereto, one face of which forms the floor of the opening in the squeeze die between the inner faces of the pressure dies.

17. In mechanism of the character described; a die unit having an outer member, an inner member movable within the outer member, each member having oppositely disposed slots with inclined bottom walls; a plurality of pressure dies arranged about a common center, each pressure die having a portion thereon that projects into two of said oppositely disposed slots when in register with each other and having an intermeshing engagement with one of the members at an angle to the side walls of the slots.

18. In mechanism of the character described; a die unit having an outer member, an inner member movable within the outer member, each member having oppositely disposed slots with inclined bottom walls, the slots in the second member having a guide groove in a wall thereof; a plurality of pressure dies arranged about a common center, each die having a portion thereon that projects into two of said oppositely disposed slots when in register with each other and having an intermeshing engagement with the said guide groove.

19. Mechanism for producing a nut or similar blank having a portion thereof substantially cylindrical in cross section and another portion substantially polygonal in cross section, comprising in part, a cavity die to receive a cylindrical portion of a workpiece, and a die that reshapes that portion of the workpiece outside of the cavity die by the application of pressure to the workpiece, substantially perpendicular to its length

and without distortion of the metal within the first mentioned die.

20. Mechanism for producing a nut or similar blank having a portion thereof substantially cylindrical in cross section, and another portion substantially polygonal in cross section, comprising in part companion tools, one of which has a cavity that in cross section is substantially the same size and shape as one end of the workpiece, and another tool having a cavity of variable size; and mechanism for actuating the last mentioned tools whereby the size of the cavity will be reduced and pressure applied to the workpiece perpendicular to the length of the cavity and thereby change the shape of the workpiece outside of the first mentioned cavity, and without distortion of the shape of any other portion of the workpiece.

21. Mechanism for producing a nut or similar blank having a portion thereof substantially cylindrical in cross section and another portion substantially polygonal in cross section, comprising companion tools that form an enlarged portion on a cylindrical workpiece; a die having a cavity, into which is projected that portion of the workpiece having a lesser diameter; and a die that applies pressure to that portion of the workpiece having a larger diameter at substantially a right angle to its length and without distortion of the metal within the said cavity.

22. In mechanism of the character described; a die unit having an outer member and an inner member movable within the outer member, each member having oppositely disposed slots with inclined bottom walls; a cavity die in one end of the inner member; and a plurality of pressure dies arranged about a common center and movable across the face of the cavity die, each pressure die having a portion thereon that projects into two of said positively disposed slots when in register with each other.

23. In mechanism of the character described; a die unit having an outer member and an inner member movable within the outer member; a cavity die in the inner member; and a plurality of pressure dies arranged about a common center, each pressure die having engagement with the inner member whereby one face thereon will move radially in substantially the same plane as the exposed face of the cavity die.

24. In mechanism of the character described; a die unit having an outer member, an inner member movable within the outer member, each member having oppositely disposed slots with inclined bottom walls; a plurality of pressure dies arranged about a common center, each pressure die having a portion thereon that projects into two of said oppositely disposed slots when in register with each other and in some of their relative positions being out of contact with the bottom walls of said slots.

25. In mechanism of the character described; a die unit having an outer member and an inner member movable within the outer member, each member having oppositely disposed slots within inclined bottom walls; a cavity die within one end of the inner member and a plurality of pressure dies arranged about a common center movable across the end of the second member and held against axial movement relative to the second member.

RICHARD LESTER WILCOX.
